UNITED STATES PATENT OFFICE.

OLIVER B. REYNOLDS, OF ELGIN, ILLINOIS.

WAGON-BOX.

No. 874,704.

Specification of Letters Patent.

Patented Dec. 24, 1907.

Application filed January 20, 1906. Serial No. 296,959.

To all whom it may concern:

Be it known that I, OLIVER B. REYNOLDS, a citizen of the United States, residing at Elgin, in the county of Kane and State of Illinois, have invented a new and useful Improvement in Wagon-Boxes, of which the following is a complete specification.

This invention relates to wagon boxes, and more particularly to the box trimmings, the object being to provide a wagon box in which the exposed edges shall be protected and strengthened in a very simple and effective manner, and to also prevent the box from warping and twisting. Wagon boxes heretofore manufactured, so far as known to applicant, were trimmed with strap iron, which did not materially strengthen the sides of the box or afford protection against water entering between the guard strip and box edge, and it is these objections which the present invention seeks to overcome.

Referring to the accompanying drawings—Figure 1 represents a side elevation of the rear end of a wagon box or body, to which is attached my improvement. Fig. 2 is an enlarged perspective, partly in section, of a portion of the wagon box shown in Fig. 1, designed to illustrate the manner of securing the beaded channel in position, and Fig. 3 is a similar view showing the attachment of a plain channel bar to the edge of the box. Fig. 4 is an end perspective of a side of the box showing the manner in which the channel bar is attached thereto. Fig. 5 is a fragmentary side elevation of the rear end of one of the wagon box sides, with a portion of the channel bar removed in order to show the grooves for receiving the tongues on the flanges of said bar, and Fig. 6 is an elevation of the part shown in Fig. 5 but viewed edge-wise. Fig. 7 represents an end elevation of a beaded channel bar provided with inwardly projecting tongues on the lower end of the flanges thereof. Fig. 8 is a corresponding view of a plain channel bar, and Fig. 9 represents an end view of a plain channel bar with the ends cut and folded together.

In the drawings, 1 designates the side board of a wagon box, 2 the bottom board, and 2¹ a sheet metal plate secured to the upper surface of the bottom. To the rear end of the bottom 2 is hinged the end gate 3, the pivotal axis thereof being at 4, and beneath the rear of the said bottom is fixed the cross bar 5.

The upper edges of the side boards 1 of the

box are protected and strengthened by means of the channel bars 6, the channel bars being preferably beaded, as shown in Figs. 1, 2 and 7. The laterally extending bead 7 is formed on the upper and outer edge of the bar, thereby presenting a wider upper surface of the box edge and also adding strength to same. This bead 7 may be omitted and plain channel bars, as 6¹, employed, as shown in Figs. 3 and 8. The cleat 1¹, secured to the board 1, forms a filler for said bead. The channel bars are held in place by means of the rivets 8, but to further insure a perfect fastening small inwardly projecting tongues 9 are formed on the lower or free edge of the flanges of the channel bars, these tongues being pressed into the corresponding grooves 10 in the side boards 1. These tongues not only afford a better means of fastening for the channel bars, but also effectually prevent water entering between said bar and side board and give additional strength to the cross section of the bar.

The manner of fastening the channels to the ends of the side boards of the wagon box is shown in Figs. 4, 5, 6 and 9. The grooves 10, if desired, may be omitted from the top, as the tongues 9 may readily be pressed into the wood when extending lengthwise of the grain, but said grooves are quite necessary at the ends. The vertical channels on the rear ends of the side boards are cut out at their corners and bent inwardly as shown in Figs. 4 & 9 thus forming at their upper ends flange projections as 6², which engage the top corner of the side boards and afford protection for same.

What I claim as my invention and desire to secure by Letters Patent is:

1. A wagon box having the edges of the side boards thereof covered with channel bars, which are clenched securely thereto, said channel bars being provided with a laterally extending bead, substantially as and for the purpose specified.

2. A wagon box having the edges of the side boards thereof covered with channel bars, which are clenched securely thereto, said channel bars being provided with inwardly projecting tongues on the lower edge of the flanges thereof, substantially as and for the purpose specified.

3. A wagon box having the edges of the side boards thereof covered with channel bars, which are clenched securely thereto, said channel bars being provided with lat-

erally extending beads at the upper side and with inwardly projecting tongues on the lower edge of the flanges thereof, substantially as and for the purpose specified.

5 4. A wagon box having the edges of the side boards thereof covered with channel bars, which are clenched securely thereto, said channel bars being provided with inwardly projecting tongues on the lower edge

of the flanges thereof, the said flanges being 10 turned in at their end to form a continuous flange about the corners of the wagon box, substantially as and for the purpose specified.

OLIVER B. REYNOLDS.
